W. B. TITUS & J. W. PASHINSKY
SELF ADJUSTING SHAFT BEARING.
APPLICATION FILED JAN. 5, 1917.

1,230,628.

Patented June 19, 1917.

UNITED STATES PATENT OFFICE.

WALTER B. TITUS AND JEFF W. PASHINSKY, OF CEDAR RAPIDS, IOWA.

SELF-ADJUSTING SHAFT-BEARING.

1,230,628.

Specification of Letters Patent. Patented June 19, 1917.

Application filed January 5, 1917. Serial No. 140,853.

To all whom it may concern:

Be it known that we, WALTER B. TITUS and JEFF W. PASHINSKY, citizens of the United States, residing at Cedar Rapids, in the 5 county of Linn and State of Iowa, have invented new and useful Improvements in Self-Adjusting Shaft-Bearings, of which the following is a specification.

The present invention has relation to a 10 shaft bearing comprehending particularly the self-adjusting type for automatically compensating the wear of the parts, and adapted for use with rotating shafts of various types, but especially adaptable for 15 power transmission shafting of an automobile, the crank shaft of an internal combustion engine or the like places familiar to those versed with the art.

An object of the invention resides in the 20 production of a shaft bearing of the above stated character of such type as to improve and simplify the construction and operation, and comparatively simple and inexpensive to manufacture, reliable and efficient in use, 25 and capable of ready adjustment.

A still further object of the invention is the provision of a bearing box wherein the supporting arms are detachably connected thereto, and the parts associated with said 30 arms are adapted to be readily assembled or disassembled, whereby should any of such parts become broken the damage can be readily remedied by the replacement of an additional part at a minimum amount of 35 expense.

Furthermore, we contemplate providing a cap detachably supported on the arms of the box through the employment of keys and the keys being so constructed and associated 40 with other parts of the bearing to adapt the cap for automatic adjustment to compensate for the wear of the shaft.

With the above and other objects in view, the invention consists in the novel features, 45 details of construction and combination of parts which will hereinafter be more fully set forth, illustrated in the accompanying drawing and pointed out in the appended claims.

50 Figure 1 is a perspective view of the connecting rod and its parts assembled for use; Fig. 2 is a vertical sectional view; Fig. 3 is a perspective view of one of the keys; 55 Fig. 4 is a detail perspective view of the

shaft box with one of the arms removed therefrom; and

Fig. 5 is a perspective view of one of the arms.

Referring more particularly to the accompanying drawing, in which like characters of reference refer to corresponding parts in the several views, 5 denotes a connecting rod having formed on one end thereof a shaft box 6 having a semi-circular recess 7 for the 65 reception of the movable bearing ring 8 in which the shaft 9 is inserted. Formed in the opposite side walls 10 of the shaft boxing is a pair of spaced vertically arranged guideways 11 and the side and bottom walls of the lower ends of said guideways being beveled as indicated by the character 12, the purpose of which will be hereinafter more 70 fully set forth. Detachably inserted through each of the guideways 11 is a flat rectangular 75 supporting arm 13 arranged in spaced relation with respect to the shaft box and to opposite sides of the semi-circular recess. The character 14 denotes a detachable cap provided with a semi-circular recess opening 80 out through the under side thereof and adapted to fit over the removable bearing 8. This cap is likewise provided at opposite 85 sides of the semi-circular recess with a pair of vertically arranged rectangular guideways 15 for slidably supporting the cap on the upper protruding extremities 16 of said arms, adapting the cap for a vertical sliding movement. The lower end of each of the supporting arms 13 is provided with a head 90

17 having beveled flanges 18; consequently when the supporting arms are attached to the shaft box, the beveled flanges 18 of the head will engage with the beveled walls 12 of the guideways 11 and adapt the head to be wedged in the guideways and dispose the head flush with the outer contour of the shaft box, forming a tight and firm connection of the supporting arm with said shaft box. These supporting arms 13 are of a length exceeding the vertical extent of the aligned guideways 11 and 15, of the respective shaft box and cap, whereby permitting the upper extremities 16 of the arms to protrude beyond the upper plane of the cap, and these protruding 100 extremities of the arms have formed therein a substantially elongated slot 19. The guideways 15 of the movable cap open out in the transverse groove 20 formed in the upper 105 end of said cap, and seated within the groove 110

20 of the cap and lengthwise thereof is a pair of keys 21 having their shanks 22 projected through and loosely mounted in the slots 19 formed in the projecting extremities 6 16 of the supporting arm for operatively associating the cap with said boxing. Detachably associated with the cap 14 and arranged in the cylindrical axial opening 23 of the cap is a post 24 having an exteriorly threaded shank 25 and a head 26. The head 26 of the post snugly engages in a recess formed in the wall of the semi-circular recess thereof, to prevent any accidental displacement of the post from said cap. This head 26 is lodged 10 between the confronting faces of the cap and one of the faces of the detachable bearing. Each of the keys 21 is provided with a wedge-shaped head 27 provided with a concaved recess 28. The purpose of such recess 15 is to permit the keys to clear the shank 24 of the post upon the removal of the keys from the slots 19 of the supporting arms. Loosely mounted on the post 24 is a rectangular block 29 having downwardly beveled ends 30, the beveled ends 30 of the block co-operating 20 with the beveled faces 31 of the heads 27. Embracing the threaded shank of the post is a compression spring 32 having one end bearing upon the upper face of the block 29 and its opposite end engaging with an adjusting nut 33 threaded upon the shank 22 of the post, and the purpose of such spring is to exert a pressure on the block 29 for constantly urging the keys in such a direction as 25 to cause the cap to press against the detachable bearings and thus automatically compensate for the wear of the bearing parts as well as the shaft. This form of construction of the device permits of the same being readily taken apart for repair or inspection, and the tension of the cap can be readily adjusted by the operation of the nut 33. After the proper adjustment or tension of the spring is acquired, the nut is locked on the shank of 30 the post by the employment of a cotter pin passing through suitable apertures 34 of the post.

From the foregoing description, taken in connection with the accompanying drawing, 50 the advantages of construction and the method of operation will be readily apparent to those skilled in the art to which the invention relates, and while we have described the principles of operation of the invention, together with the device which we now consider to be the best embodiment thereof, we desire 60 to have it understood that the device shown is merely illustrative, and that such changes may be made when desired as are within the scope of the appended claims.

What is claimed as new is:

1. A bearing comprising a shaft box, a cap movably associated with said box, means for connecting the cap to said box, means for 65 holding the connecting means against dis-

placement, and means operating between the latter mentioned means and co-operating with the confronting extremities thereof for yieldingly moving the cap section in a direction toward the shaft box. 70

2. A bearing comprising a base section, supporting arms carried thereby and each having a slot, a movable section slidably mounted on said supporting arms, keys inserted in the slot of said supporting arm, 75 and a member reposing upon the confronting ends of said keys and co-operating with the cap for yieldingly moving the latter in a direction toward the base section.

3. A bearing comprising a shaft box, a 80 movable section, a post projecting through said section, means for operatively connecting the movable section with said box, and means mounted on the post and co-operating with the latter mentioned means for yield- 85 ingly moving the movable section in a direction toward the shaft box.

4. A bearing embodying a shaft box provided with guideways, supporting arms inserted in said guideways and each having a 90 slot, a movable section slidably mounted on the supporting arms, means extending through the slots of said arms for operatively holding the sections together, and means carried by the shaft box engaging 95 with the confronting extremities of the latter mentioned means for yieldingly moving the cap section in a direction toward the shaft box.

5. A bearing comprising a shaft box, a cap 100 slidably associated with said box and provided in its upper end with a transverse groove, means seated in the groove of the box for operatively associating the cap with said shaft box, and yieldable means seated in 105 the groove of the box and exerting pressure on the first mentioned means for yieldingly moving the cap in a direction toward the shaft box.

6. A bearing embodying a shaft box, sup- 110 porting arms detachably connected with said box and provided with slots, a cap slidably mounted on said supporting arms, keys passing through the slots of the supporting arms, a block reposing upon the confronting ends 115 of the keys, and means for exerting a tension on the block to yieldingly move the cap in a direction toward the shaft box.

7. A bearing embodying a shaft box, sup- 120 porting arms detachably connected with said box and provided with slots, a cap slidably mounted on said supporting arms, keys passing through the slots of the supporting arms, a post carried by said cap, a block mounted on said post and engaging with the confront- 125 ing ends of the keys, and means for exerting a tension on the block to yieldingly move the cap in a direction toward the shaft box.

8. A bearing embodying a shaft box, sup- 130 porting arms carried by said box and each

provided in their upper extremity with a slot, a cap slidably mounted on the supporting arms, keys loosely inserted in the slots of the supporting arms, and provided with 5 beveled heads, a block reposing upon the beveled heads of the keys, and means exerting a tension on said block for forcing the keys in a direction to permit of the cap to 10 yieldingly move in a direction toward the shaft box.

9. A bearing comprising a shaft box, supporting arms having slots carried by said box, a cap slidably mounted on said sup-

porting arms, a post carried by said cap, keys having recessed heads movably mounted in the slots of said supporting arms, and means carried by the post and reposing upon the recessed heads of the keys for automatically moving the keys in a direction to permit of the cap being automatically moved in 20 a direction toward the shaft box.

In testimony whereof we affix our signatures.

WALTER TITUS.
JEFF PASHINSKY.
